UNITED STATES PATENT OFFICE.

ALONZO E. YOUNG, OF BOSTON, MASSACHUSETTS, ASSIGNOR TO FRANCIS L. KING, OF SAME PLACE.

DESIGN FOR GLASS HEAD FOR DOOR-KNOBS.

Specification forming part of Design No. 5,965, dated June 25, 1872.

Specification describing a Design for a Glass Head for Door-Knobs, Bell-Pulls, &c., invented by ALONZO E. YOUNG, of the city of Boston, county of Suffolk and State of Massachusetts.

The nature of my design consists in an improved form for that part of door-knobs, bell-pulls, &c., which may be properly designated as the head, and is fully represented in the accompanying photographic illustration and the model, to which reference is herein made.

A represents a perspective view of the front face of my improved design for a head or knob for door-knobs, bell-pulls, &c., and, by reason of the transparent glass used, the central projection D, which is on the back part, is also shown. B represents a head or knob of the same general form, but of different proportions. The sides are all plain and smooth except the central projection D on the back part. The

general form of the head is that of a parallelopiped—that is to say, a regular solid—the faces of which are six parallelograms, the opposite ones being parallel and equal to each other. The thickness of the glass between the front and back face is about three-fourths of an inch.

The end of the projection D may be ornamented with any suitable design, and, as shown, it will be exposed to view by the transparent glass.

I claim as my invention—

A design for a head or knob for door-knobs, bell-pulls, &c., made substantially in the form shown and described.

Boston, Massachusetts, April 29, 1872.

ALONZO E. YOUNG.
